ELMER L. SCHUMACHER, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS.

GOOGLES.

Application filed September 5, 1924. Serial No. 736,081.

This invention relates to improvements in goggles and has particular reference to that type of goggle used for industrial eye protection purposes.

5 One object of the present invention is to provide an eye protection goggle which will be interiorly ventilated and so constructed as to prevent entrance of injurious light rays and foreign substances behind the lens.

10 Another object is to provide such a device with non-metallic eye cups which will be suitably reinforced in the lens receiving end.

15 Another object is to provide a non-metallic eye cup for a goggle having an improved lens holding means.

A further object is to provide a goggle which will be strong and durable in service, economical of manufacture and an improvement in the art.

20 Other objects and advantages will be apparent from the following description taken in connection with the accompanying drawings, wherein are shown several embodiments of the device.

25 In the drawings, forming a part of this invention,

Figure 1 is a top plan view of a goggle made in accordance with my invention;

Figure 2 is a side elevation thereof;

30 Figure 3 is a sectional view on line 3—3 of Figure 1;

Figure 4 is a sectional view on the line A—A of Figure 1;

35 Figures 5 and 6 are views similar to Figure 3 and illustrating two possible modifications.

Similar reference characters designate corresponding parts throughout the several views.

40 In producing my improved goggle I provide a pair of eye cups 10, preferably made of tubular material, and having their rear edge suitably curved as at 11 to readily fit the contour of the face of the person wearing same, and this edge 11 may be bent back upon itself as at 12 (Figure 3), or it may be suitably padded and reinforced in any other desirable manner known to those skilled in the art.

50 Referring especially to Figures 3 and 4, I provide an annular member 13 arranged

interiorly of the eye cup 10, said annular member being preferably but not necessarily formed of metal, such as aluminum. This annular member is grooved approximately 55 midway of its length so as to form an air chamber 14, which is bounded on three sides by the material of the annulus 13 and upon the fourth side by the inner periphery of the eye cup. By offsetting the material of the annulus 13 as I have to provide the air chamber 14 I also form a lens receiving seat 15, upon which is placed any type of eye protection lens 16. The forward extremity of the ring 13 is interiorly threaded 60 as at 17 and engageable by a clamping annulus 18 which is adapted to hold the lens 16 firmly against its seat 15. In this form of the invention the exterior of the clamping member 18 comes flush with the exterior of 65 the eye cup 10, as clearly shown at 19.

The member 13 is provided with openings 20 whereby circulation of air is permitted between the air chamber 14 and the interior of the eye cup. Also the eye cup 10 is provided with additional openings 21 which extend into the air chamber 14, the latter mentioned openings being out of radial alignment with the openings 20. In this way it will be obvious that a suitable amount 70 of air will be allowed to circulate from the exterior to the interior of the goggle to allow for ventilation, but due to the fact that the openings 20 and 21 are out of alignment injurious light rays will not enter the goggle 75 behind the lens, neither will foreign substances such as fine metallic chips, emery, dust, etc., be allowed to get in.

The ring 13 serves to suitably reinforce the forward end of the eye cup 10 and for 80 that reason is made to be a fairly good mechanical fit, just slipped into place by hand and held by a staple or other suitable fastening means 22. I preferably provide the fastening means 22 on the inner 85 side of the eye cup and form it into an eye so as to be able to connect thereto the extremity of a flexible bridge member 23. Any suitable means may be used for holding the goggle in place, such as elastic bands 24 90 or temples, whichever may be preferable.

In the modification illustrated in Figure

5 I have formed the eye cup 10^a with a groove 26 having inwardly extending openings 27 to allow for the passage of air to the interior of the goggle. Furthermore, 5 I have formed a ring member 28 which is simply threaded at its forward end 29 for the engagement of the lens clamping ring 30. In this case the air chamber is formed by the clamping member 30 instead of by an internal annulus as in the previous form, said clamping member being provided with the necessary openings 31 out of alignment with the openings 27, for the purpose previously set forth.

15 In Figure 6 I have illustrated still another modification wherein the eye cup 10^b has a perfectly smooth periphery, both interior and exterior, and surrounded by a ring member 32 which is centrally arched as at 33 to 20 form the ventilation chamber 34. In this case also the necessary apertures are formed in the arched member 33 and in the eye cup 10^b to permit of ventilation, and the lens 16^b is seated directly against the front edge of 25 the eye cup 10^b instead of on a recessed seat.

From the foregoing it will be obvious that I have produced an improved construction of eye protection goggle which will be well ventilated and, therefore, extremely comfortable to workmen and especially adapted for use in hot work, such as welding and adjacent to various kinds of furnaces in industrial plants, but because of the staggered relationship of the openings injurious light rays will not be able to pass through the sides of the eye cup and the construction is such that it will be easy and economical of manufacture. Obviously changes may be made in 30 the proportion, arrangement and combination of parts, and I herein reserve the right to make such changes falling within the scope of the appended claims without departing from the spirit of my invention.

Having thus described my invention what I claim is:

1. In a device of the character described, a pair of concentric annular tubes, one of the tubes having a circumferential recess in the surface communicating with the other annulus, and a plurality of spaced openings therethrough communicating with the recess, the second annulus having a plurality of spaced openings in line with the recess of the first annulus but offset with respect to the openings thereto.

2. In a device of the character described, a pair of annular rings concentrically arranged, a lens adjacent one end of one of the said rings, a circumferential groove in one of the rings intermediate its ends, the ring having the circumferential groove having a plurality of openings communicating with the said groove and the other ring having a plurality of openings in line with the groove in the second ring but staggered in relation to the openings in the said second ring.

3. In a device of the character described, an annular eye cup, a lens positioned adjacent one end of the eye cup, said eye cup having a plurality of openings intermediate its ends and circumferentially arranged, an annular ring inside of and concentric with the eye cup having a circumferential groove overlying the openings in the eye cup and having a plurality of openings communicating with the groove but staggered in their relation to the openings in the eye cup.

4. In a device of the character described, an annular member having a circumferential groove intermediate its ends and a plurality of openings leading into the groove, a second annular member concentric with the first annulus and having a plurality of openings overlying the circumferential groove of the first annulus but offset with respect to the openings therein.

ELMER L. SCHUMACHER.
